Primary Examiner — Rosemary K Tarcza(74) *Attorney, Agent, or Firm* — NSIP Law(57) **CLAIM**

We claim the ornamental design for a charger for electronic device, as shown and described.

DESCRIPTION

FIG. 1 is a front perspective view of a charger for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along line 8-8 of FIG. 2; and,

FIG. 9 is a top view of the charger for electronic device in which the electronic device is provided in broken lines to illustrate an example environment.

The broken lines in FIGS. 1 and 3-8 depict portions of the charger for electronic device which form no part of the claimed design. The broken lines shown in FIG. 9 are for the purpose of illustrating environmental structure and form no part of the claimed design.
